UNITED STATES PATENT OFFICE

2,235,557

BOILER FEEDING APPARATUS

Dartrey Lewis, Boston, Mass., assignor to Manning, Maxwell & Moore, Incorporated, New York, N. Y., a corporation of New Jersey

Original application May 17, 1937, Serial No. 143,131. Divided and this application November 16, 1938, Serial No. 240,632

4 Claims. (Cl. 261—76)

This invention pertains to steam engineering,—more especially to improved apparatus for delivering heated feed water to a steam boiler, and relates more particularly to water heating means 5 of novel and improved construction designed to heat the feed water by the use of exhaust or live steam alternatively, the present application being a division of my copending application for Letters Patent of the United States Serial No. 143,131, filed May 17, 1937, for Boiler feeding apparatus, Patent No. 2,151,125, dated May 21, 1939. While in the specific application of the invention, herein chosen for convenience in illustration and description, it is shown as applied to a steam locomotive, it is to be understood that the invention is not in any way necessarily limited to such specific application but is of broad utility wherever it is desired to deliver water to a steam boiler.

In order that the functional utility of the novel heating means herein specifically described and claimed may be more fully comprehended, it is deemed desirable to describe more or less completely a feed water heating system of a desirable type in which the novel heater is included and forms an essential part.

While it is customary to deliver feed water to steam boilers by means of jet pumps of the kind known as injectors or inspirators, there are certain situations wherein pumps of mechanical type are required, either as auxiliary to or in substitution for such jet pumps, and in particular where it is requisite to preheat the feed water to a high temperature and to deliver the hot water against a high boiler pressure.

In the patents to Williston et al. No. 1,828,633, dated October 20, 1931, and Allen No. 1,849,900, dated May 15, 1932, desirable forms of apparatus are described, designed economically to preheat feed water to any desired temperature, and to deliver the heated water into the boiler against any desired pressure, the patented apparatus including a multi-stage high-speed turbine-driven centrifugal pump and a water heater of the jet condenser type having nozzles through which the water passes on its way from the first to the second stage of the pump, and in which it intimately contacts with and condenses exhaust steam from the engine. The heated water is then delivered to the second stage of the pump and by the latter is forced into the boiler.

The apparatus disclosed in the aforesaid patents is highly advantageous as compared with the early types of feed water pump and heater, being compact and relatively light in weight,—capable of application wherever it is most convenient to place it,—effective to raise the temperature of the feed water through such range as may be desired and to deliver it against the

high boiler pressures of present-day practice, and operating with a high thermal efficiency.

The present invention represents an improvement upon the apparatus disclosed in the aforesaid patents and has for its general objects the provision of water heating means which is dependable under all conditions of engine operation and capable of heating the feed water through a substantial temperature range either by the use of exhaust or live steam; to provide a jet condenser, low-pressure type of heater useful in combination with a variable speed multi-stage centrifugal type pump; to provide a feed water heater of high efficiency capable of heating the water to within 10°, for example, of the theoretical maximum when the pressure at the delivery end of the heater is kept substantially equal to that of the steam used for heating the water; and to provide a feed water heater of simple, compact and durable construction capable of 20 operation between the first and second stages of a multi-stage feed pump.

Other objects and advantages of the invention will be made manifest in the following more detailed description and by reference to the accompanying drawings, wherein

Fig. 1 is a fragmentary, diagrammatic side elevation of a locomotive equipped with feed water apparatus embodying the present invention;

Fig. 2 is a vertical transverse section, to larger scale, illustrating a by-pass valve of a desirable type for use as an element of the water heating and feeding mechanism of the present invention;

Fig. 3 is a fragmentary transverse section, to smaller scale than Fig. 2, showing a control valve 35 in association with the novel feed water heater to which the appended claims are particularly directed;

Fig. 4 is an end elevation, partly in vertical section, illustrating the control valve in association with an automatic heating valve desirable for use in the system herein disclosed;

Fig. 5 is a transverse section, to larger scale, showing the novel heating valve of Fig. 4, but with the parts in a different position;

Fig. 6 is a transverse section showing the control valve of Fig. 3, but to larger scale; and

Fig. 7 is a transverse vertical section illustrating a desirable form of operating and regulating valve useful in the mechanism of the present invention.

Referring to Fig. 1, wherein the invention is shown by way of example as applied to a locomotive, the numeral 1 designates the cab of the locomotive, 2 the tender, 3 the boiler, 4 the turret valve, 5 one of the steam chests, 6 the corresponding cylinder, and 7 the locomotive stack. From the turret valve 4, which receives live steam from the boiler, a pipe 8 leads to the operating valve 9. The operating valve here illustrated is 60

of a type generally resembling the operating valve described in the patent to Walch No. 2,056,698, dated October 6, 1936.

The valve 9 (Fig. 7) comprises a casing 10 having an inlet chamber 11 to which live steam is supplied by the pipe 8. The casing has outlet nipples 12 and 13 to which are connected pipes 14 and 15 leading respectively to the pump actuating turbine and to an automatic water heating valve hereinafter to be described. The flow of steam from the inlet chamber 11 to the outlet nipples 12 and 13 is primarily controlled by a manually actuatable balanced valve member having a main head 16 and a relatively movable pilot member 17, said pilot member and the valve head being moved one after the other in succession by the manipulation of a lever 18 having a handle which is disposed within the cab.

Preferably the flow of steam to the respective nipples 12 and 13 is further controlled by a regulating valve comprising spaced heads 19 and 20 which cooperate respectively with annular seats 21 and 22. The heads 19 and 20 are fixed to a stem 23 which is provided with an actuating handle 23^a, also located within the cab. Preferably the regulating valve is so devised, as by the provision of a suitable limiting stop, or by properly dimensioning the valve heads relatively to their seats, that, even when closed as much as possible, sufficient steam will be permitted to pass (assuming that the operating valve 16 is open) to drive the turbine and pump at a rate at which the pump will still deliver a minimum quantity of water to the boiler and also to provide sufficient live steam, if necessary, to heat the feed water.

Assuming that the valve head 16 is unseated, live steam from the boiler will pass through the pipe 14 and enter the casing 24 of the pump operating turbine. An exhaust pipe 25 conveys the exhaust steam from the turbine to some convenient point of discharge; for example, as here shown, to the locomotive stack 7.

The turbine, which may be of any desired type, is direct connected to a multi-stage centrifugal pump, preferably provided with four sets of impeller blades mounted on the same shaft and thus always turning at the same speed, such an arrangement, together with the direct connection of the pump to the turbine, saving space and weight and ensuring proper driving without the use of complicated gearing or other inefficient or uncertain connections. A direct connected turbine and multi-stage pump of this general type is more fully illustrated in the patent to Allen No. 1,849,900 above referred to, but whereas in said patented device the pump comprises but two sets of impellers, it is preferred, in accordance with the present invention, to provide four sets of impellers. However, as in the device of the Allen patent, the first set of impellers constitutes the first distinct stage and, in effect, a separate pump, and this first pump stage delivers feed water to a heater of the jet-condenser type which, in turn, delivers heated water to the first set of impellers of the second stage of the pump. For convenience in further description, the second, third and fourth sets of impellers are regarded as collectively constituting a "second" pump stage, although in actual fact the "second stage" is a three-stage pump in which the pressure of the hot water is successively boosted up to a point such that it may be delivered directly to the boiler against boiler pressure. Since the details of the pump form no essential part of the

present invention, and since its general character is clearly disclosed in the Allen patent, no further specific description is here necessary.

The locomotive tender 2 is provided with the usual water supply tank from which the hose 5 connection 26 leads to a strainer 27 from which the cold water supply pipe 28 leads to the intake of the first stage of the pump. The cold water from the first pump stage is delivered through pipe 29 to the feed water heater 30. This feed water heater, which also acts as a condenser for exhaust steam, may be located at any desired and convenient point, but is here shown as arranged near the forward end of the boiler.

The casing of the feed water heater 30 may be 15 of any desired external shape, but is here shown as of drum-like form. The interior of this casing (Fig. 3) is divided by septums 31 and 32 into an inlet chamber 33 into which the water is delivered by the pipe 29, an intermediate chamber 20 34 which receives the steam for heating the water, and a delivery chamber 35. One or more water delivery nozzles 36, mounted in openings in the septum 31, deliver the water received from the first pump stage, in the form of powerful jets, 25 into corresponding convergent-divergent ejector tubes 37 which are mounted in openings in the septum 32 with their receiving ends in the chamber 34 and their delivery ends in the chamber 35. From the chamber 35 a pipe 35^a leads to 30 the inlet eye of the second stage of the pump, and from the delivery orifice of the second stage of the pump a pipe 35^b conveys the hot feed water to the boiler check valve 40 through which it passes into the boiler.

In accordance with the present invention it is possible, throughout a substantial range of jet pressures, to heat the water to within ten degrees of the theoretical maximum (that is to say, within ten degrees of the temperature of the saturated steam used in heating it) when the pressure at the discharge of the condenser is kept substantially equal to that of the steam for heating. In order to approach this theoretical maximum it has been found that certain definite dimensional relations between the nozzles and ejector tubes are requisite. Thus the diameter of the nozzle throat should be approximately one-fourth the diameter of the tube throat and the distance between the adjacent ends of the throats 50 of the tube and nozzle should be from four to five times the tube throat diameter.

The feed water heater 30 is designed to raise the feed water delivered to it by the first pump stage to the desired temperature whether the engine is consuming steam or not (in other words, whether or not exhaust steam is available for heating the water), and to this end the present invention contemplates the provision of automatic means designed to deliver exhaust steam to the heater, so long as such steam is available or, if exhaust steam is not available, then to supply live steam to the heater but to cut off both exhaust and live steam from the heater when the pump is not operating, thereby to avoid any possibility of blowing steam back into the tank. The delivery of exhaust or live steam or the cutting off of both is determined by the action of a control valve 38 (Figs. 3 and 6) and a heater valve 39 (Figs. 4 and 5). These valves 38 and 39 are conveniently located just forward of the heater 30 (Fig. 1), the heater valve 39 receiving live steam from the operating valve 9 through the pipe 15, while valve 38 receives exhaust steam 75

from the exhaust cavities of the valve chest through the pipe 41.

The control valve 38 (Fig. 6) has a casing 42 divided by a septum 43 into an inlet chamber 44 and a discharge chamber 45. Preferably the casing 42 is bolted directly to the casing of the heater 30 so that the discharge chamber 45 is in direct communication with the intermediate chamber 34 of the heater.

The septum 43 has a large opening in which two coaxial valve seat rings 46 and 47 are seated. A valve head 48 cooperates with the seat 46, being mounted on a stem 49 which slides in a fixed guide boss 50 forming a part of the lower head of the casing. The lower end of the stem 49 is furnished with a piston head 51 which slides in a cylinder 52 formed in a downward extension of the lower head of the casing. One or more compression springs 53 tends to raise the piston and thus to hold the valve disk 48 against its seat 46. The space 54 above the piston head 51 communicates by means of a passage 55 (Fig. 4) with one of the chambers of the heater valve 39 (hereinafter more fully described). Through this passage 55 live steam is at times supplied to the space 54, thereby to drive the piston 51 downwardly in opposition to the spring 53 and thus to move the valve disk 48 away from its seat.

A check valve disk 56 cooperates with the seat 47, said disk having a tubular stem which slides on a fixed guide boss 57 projecting downwardly from the upper head of the casing. This check valve 56 tends to seat in response to the action of gravity or by fluid pressure applied to its upper side but lifts in response to pressure below it in excess of the pressure above it. When seated, the valve disks 48 and 56 are spaced apart, thereby providing between them a chamber 58 into which leads a passage 59 which communicates with a chamber of the heating valve 39.

The casing 60 of the heating valve 39 (Figs. 4 and 5) may be integral with the casing 42 of the control valve, or separate from and bolted thereto as may be preferred. The casing 60 has a central portion 61 provided with a cylindrical bore in which slides a differential piston valve comprising a stem having a head 63 (Fig. 5) at its lower end and a duplex head of larger diameter adjacent to its upper end, said duplex head comprising the spaced members 64 and 65. The several heads of this piston may be provided with packing rings if desired. As shown, the lower head 63 is of substantially smaller diameter than the upper head member 64, 65,—the cylindrical bore being smaller at its lower end to cooperate with this head 63.

Any suitable ratio of areas between the large and small ends of this differential piston valve may be employed. For example, if L equals the area of the large head and S equals the area of the small head, and P^1 equals the pressure which acts beneath the large head and P^2 equals the pressure which acts beneath the small head of this differential piston valve, then the forces on this valve are balanced when

$$\frac{P^2}{P^1} = \frac{L-S}{L}$$

The piston valve will move up or down when the ratio of P^1 to P^2 is out of balance sufficiently to overcome the friction of the piston. A suitable ratio of P^2 to P^1 is one to four and one-half.

The casing 60 has an inlet chamber 66 which receives live steam from the operating valve 75 through pipe 15, and the wall of the cylinder 61

has ports at 67 through which steam from the chamber 66 may enter the space 68 below the valve head 65. The casing also has a chamber 69 which at times communicates by means of a small port 70 with the chamber 68 and which is connected by passage 55 (Fig. 4) with the space 54 above the head of piston 51 of the control valve (Fig. 6) as above described.

The casing 60 also has another chamber 71 which, at times, communicates by means of ports 10 72^a with the space 68 below the piston head 65. Preferably, an orifice ring 73 of predetermined capacity restricts the flow of steam from the outlet chamber 71 to a predetermined maximum amount. Steam which passes through the orifice 15 73 flows through the passage 59 (Figs. 4 and 6) in the casing of control valve 38 and thus enters the space 58 between the control valve disks 48 and 56.

A pipe 74 conducts live steam from the steam chest 5 to the space within the cylinder 61 above the valve head 64, so that the latter is always subjected to high steam pressure, so long as the throttle valve is open. The cylinder 61 is provided with stops 75 and 76 at its upper and lower 25 ends, respectively, to limit movement of the differential piston valve. Preferably a drain opening 77 is provided beneath the piston head 63 to prevent an accumulation of pressure fluid beneath such head.

30

Operation

When the engine is running and exhausting steam in an amount sufficient to heat the feed water, and assuming that the operating valve has been opened to admit live steam through pipes 14 and 15 to the turbine and heater valve respectively, and further assuming that the pressure of live steam from the steam chest, acting on the valve head 64, has pushed the differential valve 40 downwardly until its lower head engages the stop 76, as shown in Fig. 5, live steam is admitted through the ports 67 to the chamber 68 and thence through the port 70 to the space 69 from which it flows through the passage 55 into the space 54 45 above the piston 51 of the control valve, thus pushing said piston downwardly and moving the control valve disk 48 away from its seat. At this time the head 65 of the heater valve piston cuts off communication between the chambers 68 and 50 71 so that no live steam can enter the latter chamber. However, chamber 44 of the control valve is now supplied with exhaust steam from the exhaust cavities of the steam chest, and this steam passes between the lowered valve disk 48 55 and its seat and enters the space 58 and lifts the check valve disk 56 from its seat. The exhaust steam then passes through the chamber 45 and into the intermediate chamber 34 of the heater device.

At the same time, live steam admitted through the pipe 14 starts the turbine and thus drives the pump, the speed of the turbine and pump being determined by the amount of steam admitted, which is regulated by the setting of the regulating 65 valve comprising the heads 19 and 20. Upon admission of exhaust steam to the chamber 34 of the heater, its first effect is to tend to clear the chamber of water by forcing it through the pipe 35^a into the second pump stage. By this time the pump has 70 picked up speed sufficient to draw water from the tank and to deliver it at substantially tank temperature and at a pressure of the order of fifty pounds per square inch, for example, to the nozzles 75 of the water heater. From these nozzles 75

the water is delivered in high velocity jets into the convergent combining sections of the ejector nozzles 37. These jets of relatively cold water entrain the exhaust steam by an ejector action, 5 condensing the steam, and thereby very effectively heating the water, some of the heat energy of the steam being converted into pressure as the water and condensate pass out through the divergent delivery ends of the tubes into the chamber 35. 10 From this chamber the water, now heated, for example to a temperature nearly approximating the temperature of the saturated steam admitted to chamber 34, enters the intake eye of the second pump stage. In passing through this second 15 pump stage, the pressure of the hot water is raised sufficiently to force it through the check valve 49 into the boiler.

So long as the engine continues to supply exhaust steam and so long as the exhaust valve remains open to supply steam for actuating the pump, the above operation continues.

If, when the engine is running and delivering exhaust steam, the operating valve be closed so as to stop the pump, the supply of steam through 25 both pipes 14 and 15 is simultaneously cut off. Since live steam is now no longer available to act on the piston 54 of the control valve, the spring 53 raises the piston 54 and closes the valve disk 48 against its seat, thus cutting off communication 30 between the condenser and the exhaust cavities of the engine. However, since valve disk 48 is held to its seat by spring pressure, it acts as a relief or safety valve in response to any accidental 35 excess pressure which might develop in chamber 58. It is to be noted that at this time steam from the steam chest is still available to act on the upper head 64 of the heater valve, thus holding the differential piston valve down in the position of Fig. 5. As soon as the valve disk 48 40 is seated, the check valve 56 returns to its seat and so prevents feed water from flowing into the control valve chamber 58 and thence into the passage 59. The parts thus remain until the 45 pump is restarted or the engine ceases to deliver exhaust steam.

It is frequently necessary to feed water to the boiler when the engine is not running or at least is not consuming steam (as, for example, when a locomotive is drifting) but, as above pointed out, 50 it is highly undesirable to deliver cold water to a hot boiler, although under the conditions just referred to, no exhaust steam is available for heating the water. However, in accordance with the present invention, and by the automatic operation 55 of the appliances above described, the failure of the exhaust steam supply, while the operating valve is open, immediately results in the delivery of live steam to the water heater in sufficient quantity to heat the feed water. Thus, let it be assumed that the operating valve is open so that 60 live steam is being delivered to the turbine, and is also free to pass through the pipe 15 to the chamber 66. However, at this time live steam is no longer supplied by the pipe 14 to act on the 65 upper head 64 of the differential valve as the throttle is now closed. Thus unbalanced steam pressure in the space 68 reacts against the lower side of the head 65 of the differential valve and raises this valve to the position shown in Fig. 4. 70 In this position the lower head 63 closes the port 70, while at the same time the space 68 is put into communication with the chamber 71 by means of ports 72a.

Live steam now flows through the pipe 15, 75 chamber 68, and the ports 72a into the chamber

71, and through passage 59 into the space between the valve disks 48 and 56 of the control valve. The valve 48 is now closed by the spring 53 (since steam is cut off from the chamber 54 by the valve head 63), but the check valve 56 is lifted by the 5 live steam in the chamber 58 which is now free to flow into the chamber 34 of the heater where it is entrained by the water jets and heats the water in the same way as the exhaust steam, as above described.

By suitably designing the heads 19 and 20 of the regulating valve, it is possible to provide suitable amounts of live steam for heating the water in accordance with the amount of water being pumped. For instance, with the pump operating 15 at 100% capacity, sufficient live steam may be provided to raise the water temperature through 120°; at 50% capacity, sufficient steam may be provided to raise the water through 80°; and at 25% capacity, sufficient steam may be admitted 20 to raise the water through 60°, etc. Obviously other proportions may be provided for by suitably relating the sizes of the valve heads 19 and 20 and the orifices with which they cooperate. As 25 already noted, it is preferred to make the valve heads 19 and 20 of such size relatively to the passages through the valve seats as to ensure turbine driving steam sufficient to create a delivery pressure such as to force some water into the boiler so long as the operating valve is open.

As soon as the throttle is opened to admit steam to the steam chest and cylinder to start the engine, pressure is applied to the upper end of the differential valve 64, thus forcing the latter valve down and reopening port 70 while cutting 35 off the passage of live steam to the chamber 71, and at the same time readmitting exhaust steam to the chamber 41 of the control valve.

While the apparatus as above described is operative for the intended purpose and without 40 adjunctive features, it is preferred to provide an automatic pressure equalizer for the delivery chamber 35 of the heater in order to ensure optimum conditions of operation at all capacities of the pump.

If the pump be considered as consisting of two separate pumps, one of which delivers to the nozzles of the heater and the second of which delivers to the boiler, it will be clear that the second pump delivers against a substantially 50 constant head; that is to say, the boiler pressure, but receives its supply from a source of pressure which may vary in accordance with the speed of the first pump. On the other hand, the first pump receives its supply at a substantially 55 constant head but delivers into a heater in which the pressure may vary substantially in accordance with the speed of the second pump.

Moreover, since the pump is of the centrifugal type, there is a definite minimum speed at which 60 the second stage will deliver any water at all to the boiler, since at any lesser speed the water is merely churned by the impeller blades and remains within the pump casing. Preferably the pump is so designed that at a selected speed, for 65 example, maximum pumping capacity, the first stage delivers such an amount of water to the heater nozzles as will (when combined with the condensed heating steam) substantially equal the amount withdrawn from the heater by the second 70 stage of the pump for delivery to the boiler.

However, since the impellers of both the first and second stages of the pump are mounted on the same shaft and necessarily turn at the same speed, any reduction in the speed of the second 75

stage, for cutting down the supply to the boiler, results in a similar reduction in speed of the first stage.

To obtain a clear conception of what happens when the speed of the pump is reduced, it is convenient to consider that extreme condition which exists when the speed is reduced just to the point at which the second stage of the pump will no longer deliver any water to the boiler. Manifestly, when this condition obtains, the first pump stage continues to discharge water into the heater, although at a lesser rate, and since no water is now withdrawn from the heater by the second pump stage, pressure rapidly builds up in the delivery chamber 35 of the heater. As one result of this condition, the entire heater and the passages leading to it soon fill with water so that no further condensation can take place.

As a matter of fact, the amount of boiler pressure against which a jet-condensing heater of the type above described will operate is very strictly limited. Moreover, within the range of pressures within which such a jet-condensing heater will actually operate without choking, the amount of steam condensed rapidly grows less as the back pressure in the delivery chamber in the heater increases, and although in theory the building up of a high back pressure at the inlet eye of the second pump stage (at low speeds) will tend eventually to equalize the output of the first and second stages of the pump, the choking of the condenser constitutes the real limit which determines the minimum practical speed of operation.

On the other hand, while excessive back pressure at the intake eye of the second pump stage is not permissible, insufficient back pressure at this point is also undesirable since at the high temperature of the feed water, low pressure results in foaming and cavitation, with loss of pump capacity and efficiency. Preferably the back pressure at the inlet of the second pump stage should be in excess of the boiling pressure corresponding to the water temperature, and when using a jet-condenser heater designed as above described, this temperature is approximately within ten degrees of the temperature of saturated steam at the pressure supplied to the heater for heating the water.

Accordingly, it is highly desirable to provide automatic means for maintaining a predetermined pressure in the delivery chamber 35 of the heater. To this end, the present invention contemplates the provision of an automatic by-pass valve operating to relieve the pressure in the delivery chamber 35 whenever, during the operation of the pump, it tends to rise excessively.

One desirable form of by-pass valve is shown at 78 in Figs. 1 and 2. This valve is conveniently located adjacent to the pump and is here illustrated as mounted directly upon the pump casing, although this is not necessary. This by-pass valve comprises a casing 79, the interior of which is divided by a septum 80 into an inlet chamber 81 and an outlet chamber 82. The inlet chamber 81 is always in communication by means of pipe 35^a with the delivery chamber 35 of the heater, preferably communicating with pipe 35^a just where the latter enters the inlet of the second stage of the pump. The outlet chamber 82 is connected by means of a pipe 83 and a hose connection 84 to the water tank in the tender.

The septum 80 of valve casing 79 has an open-

ing for the reception of a cylindrical guide 85 whose upper edge constitutes an annular valve seat with which cooperates a by-pass check valve 86. This check valve has guide wings which slide in the guide 85, and the valve also preferably has an upstanding central boss 87 for engagement by the lower end of a loading piston 88 which slides in a bore in a hollow plug 89 forming the top of the casing 79. Above the piston 88 is a space 90 which communicates by means of a pipe 91 with the chamber 58 between the valve disks 48 and 56 of the control valve 38, the pipe entering said chamber at 91^a. Normally, the valve 86 is held to its seat by the weight of piston 88, assisted by the fluid pressure in the space 90, but in response to excess pressure at the intake of the second pump stage, the valve 86 rises and allows water to escape from the chamber 35 through the pipe 35^a and thence through the chambers 81 and 82 and the pipe 83 to the tank in the tender.

By drawing the steam which applies pressure to the piston 88 from the chamber 58 of the control valve, it is assured that the pressure in the chamber 90 will never exceed that of the steam supplied for heating. At times, due to improper operation of the heater, the pressure in the intermediate chamber 34 of the heater may be higher than that of the heating steam, but the check valve disk 56, which is interposed between the chamber 34 and the inlet 91^a to the pipe 91, effectively prevents any higher pressure than that of the heating steam from acting on the piston 88. Normally the heating steam has a pressure which may vary from zero to twenty-five pounds per square inch, it being noted that even when live steam is being used for water heating, such steam is so throttled in passing through the various pipes and valves and through the orifice 73 that when it reaches the chamber 58, its pressure is not substantially higher than that of the exhaust steam which is used under other conditions.

If the piston 88 and the valve 86 be of the same effective diameter, the check valve 86 would, in theory, open as soon as the pressure in chamber 81 even slightly exceeds the pressure of the heating steam. Since there is some drop in pressure between the chamber 35 of the heater and the chamber 81 of the by-pass valve, it may be desirable, in order to maintain the pressure in the heating chamber 35 equal to that of the heating steam used, to provide a spring 92 to react with a predetermined upward pressure on the valve 86 so as to compensate for the pressure drop between the chambers 35 and 81. This spring may, for example, be so arranged as to exert a pressure corresponding to a pressure of from one to five pounds per square inch acting over the effective area of the valve 86.

While the check valve disk 56 of the control valve device forms a convenient check to prevent excessive pressure from entering the chamber 90, any other check valve appropriately arranged may be employed in so far as maintenance of uniform pressure in the by-pass valve chamber 90 is concerned.

While, as shown, the spring 92 is a compression spring disposed beneath the valve disk 86, it may, as well, be a tension spring arranged to act upwardly on the piston 88. In fact, this latter arrangement has certain advantages; for example, it leaves the valve 86 always free to seat in response to any tendency whatever of fluid to

flow in reverse direction from the chamber 82 to the chamber 81.

Preferably a pressure gauge 94 and a thermometer device 95 are disposed within the cab and connected to the delivery pipe 35^b of the heater so as to inform the engineer, at all times, of the pressure and temperature conditions of the feed water when the pump is in operation.

While a certain desirable embodiment of the invention has herein been shown and described by way of example, it is to be understood that the invention is not necessarily limited to the precise arrangement herein illustrated but is to be regarded as of broad scope and as inclusive of 15 any and all equivalents.

I claim:

1. Apparatus of the class described wherein a multi-stage variable speed centrifugal pump is driven by a steam turbine and in which the 20 water is heated on its way from one pump stage to another, characterized in that the means for heating the water is in a heater of the jet condenser type having water delivery nozzles and corresponding convergent-divergent ejector tubes 25 each axially aligned with one of said nozzles, the diameter of the nozzle throat being approximately one-fourth that of the tube throat, and the throat of the nozzle being spaced from that of the tube a distance of from four to five times 30 the tube throat diameter whereby, throughout a substantial range of jet pressures, the water can be maintained at a temperature which is within approximately 10° of that of the steam employed in heating it.

35 2. A feed water heater for use in a boiler feed system, said heater comprising a casing having transverse septums defining an inlet chamber, an intermediate chamber and a delivery chamber, respectively, a water delivery nozzle mounted 40 in an opening in the septum which separates the inlet and intermediate chambers, and a convergent-divergent ejector tube mounted in an opening in the septum which separates the intermediate and delivery chambers, said nozzle and 45 tube being in axial alignment, the diameter of the nozzle throat being approximately one-fourth that of the tube throat whereby, throughout a substantial range of jet pressures, the water can be maintained at a temperature which is within 50 approximately 10° of that of the steam employed in heating it.

3. A feed water heater for use in a boiler feed

system, said heater comprising a casing having transverse septums defining an inlet chamber, an intermediate chamber and a delivery chamber, respectively, a water delivery nozzle mounted in an opening in the septum which separates the 5 inlet and intermediate chambers, a convergent-divergent ejector tube mounted in an opening in the septum which separates the intermediate and delivery chambers, said nozzle and tube being in axial alignment, the adjacent ends of the tube 10 and nozzle throats being spaced apart a distance which is from four to five times the diameter of the tube throat and the throat diameter of the tube being approximately four times that of the nozzle, means for admitting water to the 15 inlet chamber, means for admitting heating steam to the intermediate chamber, means providing an outlet from the delivery chamber, and valve means operative to keep the fluid pressure in the outlet from the delivery chamber substantially equal to the pressure of the heating steam whereby, throughout a substantial range of jet pressures, the water can be maintained at a temperature which is within approximately 20 10° of that of the steam employed in heating it. 25

4. A feed water heater for use in a boiler feed system, said heater comprising a drum-like casting having transverse septums defining an inlet chamber, an intermediate chamber and a delivery chamber, respectively, a plurality of water 30 delivery nozzles mounted in openings in the septum which separates the inlet and intermediate chambers, a similar number of convergent-divergent ejector tubes mounted in openings in the septum which separates the intermediate and delivery 35 chambers, each nozzle being in axial alignment with a corresponding tube, the nozzle throat diameter being substantially one-fourth the diameter of the corresponding tube throat, means for delivering water under pressure to 40 the inlet chamber, means for delivering heating steam to the intermediate chamber, means providing an outlet from the delivery chamber, and pressure-loaded valve means operative automatically to keep the fluid pressure in the outlet 45 from the delivery chamber substantially equal to the pressure of the heating steam whereby, throughout a substantial range of jet pressures, the water can be maintained at a temperature which is within approximately 10° of that of the 50 steam employed in heating it.

DARTREY LEWIS.
